UNITED STATES PATENT OFFICE

2,429,172

STEERABLE BABY CARRIAGE

Raymond J. Sarasin, Fitchburg, Mass., assignor
to F. A. Whitney Carriage Company, Leomin-
ster, Mass., a corporation of Massachusetts

Application November 6, 1945, Serial No. 626,928

6 Claims. (Cl. 280—48)

1

This invention relates to steerable baby carriages and the object is to provide an improved construction having means normally tending to return the parts to the centralized position for straight-ahead running, which means will be efficient and sensitive and present no undue impediment to intentional steering movements.

My invention will be well understood by reference to the following description taken in connection with the accompanying drawings, wherein:

Fig. 1 is a bottom plan view of the carriage;

Fig. 2 is a partial bottom plan showing the parts in a position assumed when a turn is being made;

Fig. 3 is an enlargement of a portion of Fig. 2; and

Fig. 4 is a section on the line 4—4 of Fig. 3.

Referring to the drawings, the carriage there shown comprises a body 10 supported substantially centrally thereof and at either side from the end portions of a cross-member 12 to which are joined by vertical pivots 14 two non-parallel longitudinal reaches 16, the ends of which are connected by vertical pivots 18 to front and rear nonrotatable wheeled axles 20. Herein the reaches incline inwardly from rear to front forming with the intervening segments of the axles an isosceles trapezoid when the parts are centralized and the carriage is pointed straight ahead. These parts form a deformable linkage and if, for example, a lateral force is applied toward the right on the cross-member 12, the axles will be turned in a direction to make a turn to the left (Fig. 2), steering being effected primarily by turning movement of the front axle although herein the rear axle also moves in a lesser amount. In the preceding sentence I have used, and hereinafter I shall use, "left" and "right" with reference to the figures of the drawings, and since these are bottom plans the directions referred to are opposite to those which a person trundling the baby carriage would call left and right.

Describing further details of the carriage illustrated, the cross-member 12 is herein shown as supporting at its ends the longitudinal springs 34 by which the body proper is suspended. The cross-member swings between U-shaped members 48 (Fig. 4) attached to the reaches 16 and which limit the angular movements of the latter. The pivot bolts 14 have an extended bearing in these members 48 and in the central portions of inwardly facing arcuate elements 38, the outer ends of which are rigidly secured to the springs 34.

2

The construction as so far described is not novel to the present application but is here disclosed as an illustrative and indeed a preferred construction of steerable carriage.

5 It has hitherto been proposed to provide in a steering carriage oppositely acting springs such as ordinary helical coil tension springs for maintaining the same normally in position for straight-ahead running. I have found that if 10 such springs are to be effective on small displacements of the gear, they must be applied under considerable initial tension. Consequently the mechanism will be retained with considerable force in the centralized position, adversely affecting the ease with which steering could be effected. In the arrangement which I am about to describe oppositely acting spring devices are provided which, while conveniently and desirably under initial stress, exert no or substantially no force 15 on the steering mechanism in the normal position. One such device is additionally stressed as a turn is made in the appropriate direction, but the other is idle, the adjacent parts moving freely away therefrom.

20 Such devices are conveniently embodied in entirely separate and independent spring units as herein shown, wherein I illustrate right and left torsion springs 52 having central coils encircling the pivots 14 and arms 53 and 55 having hooked ends which engage respectively the cross-member 12 and the adjacent reach 16 at the forward side of the cross-member. These locations for the springs of the pair are exemplary of locations adjacent to parts the angular relation of which varies in opposite sense in the 25 steering movement. Thus in moving from the position of Fig. 1 to the position of Fig. 2, the angle between the cross-member 12 and the left-hand reach diminishes while that between the 30 cross-bar and the right-hand reach increases.

The springs may be positioned by a trapezoidal plate 57 held by the pivot 14 and having (see Fig. 4) downturned flanges 59 opposing the arms 53 and 55. The spring is maintained under 35 initial compressive stress but its resilient expansive action is limited by the flanges, and the arrangement is such that in the normal position of the parts as illustrated in Fig. 1 the ends of the arms will just about touch the cross-bar 12 and the reach 16 but no force, or a very slight force, will be exerted on those parts.

Now, if a turn is made to or toward the position of Fig. 2, there is lost motion between the right-hand spring and the adjacent parts. Although the spring is under initial stress between

the flanges 59 of plate 57, it is not operative to exert any influence on the steering action. At the left-hand side of Fig. 2, however, the legs of the spring are further pressed together in the diminishing angle between the cross-bar 12 and the left-hand reach 16 and immediately but sensitively this spring exerts a force tending to restore the parts to the position of Fig. 1. If the turn is to the opposite direction, the left-hand spring will be idle while the right-hand spring will be further compressed.

A carriage constructed as described rolls forward smoothly without yawing, but can be easily steered when desired.

I am aware that the invention may be embodied in other specific forms without departing from the spirit or essential attributes thereof, and I therefore desire the present embodiment to be considered in all respects as illustrative and not restrictive, as is in fact clear in several matters from the description itself. Reference is to be had to the appended claims to indicate those principles of the invention exemplified by the particular embodiment described and which I desire to secure by Letters Patent.

I claim:

1. A steerable baby carriage having a body supporting under-frame and a pair of non-rotatable wheeled axles incorporated in a linkage deformable to enforce a horizontal swinging movement of at least one of the axles on application of a transverse force to one of said incorporated elements and a pair of spring devices associated with the linkage which, in the normal straight-ahead position of the parts, exert substantially no force on the linkage and are constructed and arranged to be stressed respectively as the turns are made in opposite directions while there is lost motion between the companion spring device and the parts of the linkage adjacent thereto.

2. A baby carriage comprising a body supported substantially centrally and at either side thereof by vertical pivots on a pair of longitudinal reaches which extend in non-parallel relation and are pivoted by vertical pivots at their ends to front and rear non-rotatable wheeled axles, the pivotal points being arranged to cause turning movement of at least one of the axles when a lateral pressure is exerted on the body, and a pair of spring devices normally substantially unstressed by any of said parts, one located to be stressed by the relative angular movement of adjacent parts as a turn is made in one direction while the corresponding parts adjacent the other have lost motion relative to said other and conversely when the turn is made in the other direction.

3. A baby carriage comprising a body supported from front and rear axles, means for angularly moving one of the axles relative to the body to steer the carriage, a pair of springs positioned respectively adjacent parts the angular relation of which varies in opposite sense in the steering movement, means placing the springs under stress and delimiting the resilient return thereof, whereby said parts are substantially free from stress of the springs when the axle is in normal position for straight-ahead movement, said springs respectively being engaged and further stressed by said parts when the turn is made in one or the other direction.

4. A baby carriage comprising a body supported substantially centrally and at either side thereof by vertical pivots on a pair of longitudinal reaches which extend in non-parallel relation and are pivoted by vertical pivots at their ends to front and rear non-rotatable wheeled axles, the pivotal points being arranged to cause turning movement of at least one of the axles when a lateral pressure is exerted on the body, a pair of oppositely acting torsion springs having arms opposing parts which form angles at a pair of said pivots, one of which angles increases as the other diminishes when the vehicle is steered, and means delimiting the movement of the arms in one direction whereby the resilient stress of the springs is at least substantially neutralized in the straight-ahead position of the parts.

5. A baby carriage comprising a body supported substantially centrally and at either side thereof by vertical pivots on a pair of longitudinal reaches which extend in non-parallel relation and are pivoted by vertical pivots at their ends to front and rear non-rotatable wheeled axles, the pivotal points being arranged to cause turning movement of at least one of the axles when a lateral pressure is exerted on the body, a pair of oppositely acting torsion springs having arms opposing parts which form angles at a pair of said pivots, one of which angles increases as the other diminishes when the vehicle is steered, and means delimiting the movement of the arms in one direction whereby the resilient stress of the springs is at least substantially neutralized in the straight-ahead position of the parts, said means comprising a plate secured by the pivot and having flanges opposing the arms.

6. A baby carriage for trundling by hand comprising a body, a frame suspending the body, a pair of non-rotatable wheeled axles adjacent the ends of the body, and means for connecting the frame to the axles for supporting the body substantially centered thereon, said means consisting of links mounted on said frame at both sides of the center line of the body and pivoted to said frame and axles on pairs of transversely aligned vertical axes, the links being proportioned and arranged to enforce a horizontal swinging movement of at least one of the axles on application of a transverse force to one of said pairs as by a lateral pressure on the frame, a pair of springs positioned respectively adjacent certain of the above-recited parts the angular relation of which varies in opposite sense in the steering movement, means placing the springs under stress and delimiting the resilient return thereof, whereby said parts are substantially free from stress of the springs when the axle is in normal position for straight-ahead movement, said springs respectively being engaged and further stressed by said parts when the turn is made in one or the other direction.
